FUEL SUPPLY CONTROL MEANS

William E. Leibing, San Rafael, Calif., assignor to Leibing-Fageol Company, Detroit, Mich., a partnership composed of F. R. Fageol, Ravenna, Ohio; R. D. Fageol, Detroit, Mich.; Jessie M. Fageol, Ravenna, Ohio; W. E. Leibing, Detroit, Mich.; and D. C. Farnsworth, Veterans Hospital, San Fernando, Calif.

Application January 23, 1939, Serial No. 252,470

8 Claims. (Cl. 123—119)

This invention relates to means for controlling the supply of fuel to internal combustion engines and is more particularly concerned with automatic means for restricting or cutting off the fuel supply during conditions of operation of the engine when flow of fuel is not desired, which device is uniformly operable regardless of external atmospheric conditions.

The present invention, in its preferred embodiment, is intended as an improvement over the carburetor and "Degasser" disclosed in Patent No. 2,134,667 which embodies automatic control means for regulating the flow of fuel to an internal combustion engine.

The control of the above mentioned patent, which specifically embodies a pressure responsive element having one side exposed to the atmosphere and the other side selectively subjected to pressures from the intake manifold of an engine has proven highly satisfactory when used in localities and under conditions where the atmospheric pressure conditions do not vary appreciably.

Some difficulty has been experienced, however, where a vehicle equipped with this type of "Degasser" has been driven between localities of radically different atmospheric pressure as in mountainous regions. Since the "Degasser" adjustment is normally balanced in accordance with the atmospheric pressure in a given locality it will be seen therefore that this adjustment becomes substantially unbalanced when the atmospheric pressure changes. This causes undesirable inaccurate operation of the "Degasser."

The following table lists a few figures taken from Official U. S. Observatory Reports to illustrate the gradation of normal atmospheric pressures at various altitudes.

Altitude (ft.)	Pressure (inches of HG)
Sea level—0.....	29.92
800.....	29.00
1,600.....	28.00
2,800.....	27.00
3,800.....	26.00
4,900.....	25.00
6,000.....	24.00
7,100.....	23.00
8,300.....	22.00
9,600.....	21.00
10,000.....	20.07

Besides changing with the altitude, the atmospheric pressure is appreciably affected by general weather conditions and the pressure usually drops during stormy weather.

One of the major problems faced in improving the operation of prior devices of the type herein described has been to provide a pneumatic fuel supply control, the operation of which is independent of changes in atmospheric pressure and temperature. A further problem has been found where a flexible diaphragm is used and is subjected to intense heat, as where the control is used on a rear engine drive truck or bus, the material of the diaphragm under such conditions being often liable to deterioration with consequent objectionable and unreliable operation.

Further room for improvement has been found in the operation of the fuel supply cut-off mechanism. Usually a metallic needle valve cooperating with a metallic seat is employed. This type of valve has been found to wear rapidly and soon allows leakage of fuel into the idling system at times when the fuel supply should be entirely cut off. Such wearing often causes back-fires and other undesirable engine action. Furthermore in some prior constructions, the needle valve has been located in a position whereby it has been necessary to disassemble the entire unit to recondition the valve seat or loose a sticky valve stem.

Further room for improvement has been found because of the condition when air usually leaks into the idling system past the loosely fitting shut-off valve mechanism heretofore provided in some instances. This air leakage disturbs the usual idling valve air adjustment for the carburetor. Furthermore, many of these loosely fitting needle valve stems become clogged with dirt or powder from the fuel such as tetraethyl of lead thus causing the valve to become sticky in operation or even entirely frozen.

With a view to improving the operation and construction of prior "Degassers," it is a major object of the present invention to provide novel means for controlling the supply of fuel to an internal combustion engine which is uniformly and reliably operable under all atmospheric pressure or temperature conditions.

A further object of the present invention is to provide novel pneumatically operated means for controlling the supply of fuel to an internal combustion engine which means is automatically compensated for changes in atmospheric pressure so as to provide uniform and dependable operation.

A further object of this invention is to provide a novel pneumatic fuel supply control selectively actuated by suction from the intake manifold of the engine and maintained in a predetermined condition of operative balance under all atmos-

pheric pressure conditions. More specifically the pneumatic control includes a diaphragm or bellows or piston arrangement having one side subjected to atmospheric pressure and the other side subjected through a throttle controlled passage to the suction of the intake manifold.

A further object of the invention is to provide a novel pressure responsive device including means to maintain automatically a predetermined condition of balance at varying atmospheric pressure conditions.

It is still a further object of the invention to provide a pressure responsive device such as a diaphragm, bellows, piston or the like which is exposed to the atmosphere and which is balanced at least partially by forces which normally do not vary directly with changes in the atmospheric pressure wherein these forces are adapted to be automatically compensated for atmospheric pressure changes.

A further object of the invention is to provide a novel pressure responsive device wherein the pneumatic forces are at least partly balanced by resilient means such as a spring and wherein a deformable pressure actuated element such as a bellows or the like is used to vary the effect of the spring on the pressure responsive device. More specifically the spring is preferably supported or anchored upon the bellows at one end.

A further object of the invention is to provide a novel springless pressure responsive device for regulating the fuel supply to an internal combustion engine wherein the pressure responsive device is automatically compensated for changes in atmospheric pressure.

It is still a further object of the invention to provide a novel valving mechanism for cutting off the idling fuel supply in an internal combustion engine wherein metal to metal valve contact faces are eliminated to reduce wear, wherein air leakage tending to destroy the idle fuel mixture adjustment is eliminated, and wherein foreign matter is prevented from entering and clogging the valve guide passages.

Still a further object of this invention is the provision of novel means in combination with a metal to metal valve of the type herein described whereby the valve faces may be readily refaced and sticking quickly and easily remedied without disassembling the entire unit.

A further object of the invention is to provide a novel pressure responsive device for cutting off the supply of fuel to an internal combustion engine under predetermined conditions which device is automatically compensated for changes in atmospheric pressure and deformation due to changes in temperature of the material embodied in the device.

A further objection of this invention is the provision of novel means for cutting off the supply of fuel to an internal combustion engine of a vehicle as when the throttle is closed and the vehicle is driving the engine, means being provided whereby the fuel cut-off will occur at the point most favorable to the condition of the engine as regards its temperature i. e., a cold engine is favored more than a hot engine, the degree of favor varying as the engine goes from a cold condition to normal working temperature; said means also operating to favor the engine under conditions where the engine may be lowered in temperature as when the vehicle is coasting down a long hill.

Further objects of the present invention will duly appear as the description proceeds in con-

nection with the appended claims and the annexed drawings in which

Figure 1 is a section taken along line 1-1 of Figure 2 illustrating a preferred embodiment of an automatically compensating pressure responsive device constructed according to this invention, a carburetor conduit being additionally shown in Figure 1 to more clearly illustrate the invention.

Figure 19 is a section taken along line 19-19 of Figure 18.

Referring to Figures 1-5, a carburetor conduit or passage 21 forming part of the fuel intake conduit of an internal combustion engine, is arranged to conduct the fuel mixture from an up-draft carburetor to the intake manifold of an internal combustion engine and is provided with a suitable flange 22 for attachment to the intake manifold. While description is made herein of an updraft installation, it is to be understood that this invention is capable of use in a down draft installation and reference is made to an updraft installation solely for the purposes of illustration.

A throttle valve 23, preferably of the butterfly type, is pivotally mounted within conduit 21 in a suitable manner and preferably has a portion of the upstream edge modified as indicated at 24 to form a relatively thin section for a purpose

later to be described. Valve 23 may be of the conventional carburetor type or may function as a combined carburetor and governor valve with suitable mechanism connected thereto to effect automatic governing of the engine.

The "Degasser" of the present invention is preferably formed in three main housing sections 25, 26 and 27 which are preferably die cast from a suitable metal for purposes of economy of manufacture.

Section 25 is provided with a hollow boss 28 which is adapted to be received within a suitable pocket or recess 29 formed in a wall of the carburetor conduit for a purpose to be later described. A passage 31 extends through section 25 from boss 28 to an axial passage 32 which opens at the inner wall of section 25, the outer end of passage 31 being suitably plugged as shown.

Section 25 is formed with a suitable aperture 33 through which extends a valve control plunger, later to be described, and is formed with radially extending lug formations which align with similar lug formations on sections 26 and 27 to receive a plurality of elongated bolts 34 or similar fastening means for rigidly securing sections 25, 26 and 27 together. Suitable compressible gaskets 35 and 36 are provided between adjacent end walls of sections 25 and 26, and 26 and 27, respectively. Gasket 35 is suitably apertured to permit free passage of the valve plunger mechanism.

A deformable flexible metal-walled bellows 37 is positioned axially within section 26 and has its inner end sealed by a rigid plate 38 which is secured to section 25 by a pair of screws 39. When screws 39 are drawn tight, plate 38 is seated firmly against gasket 35 in gastight relation. Plate 38 is apertured axially at 41 in alignment with passage 32 and gasket 35 is suitably apertured so that passage 31 is in communication with the interior of bellows 37 through passage 32 and aperture 41.

At its other end, bellows 37 is sealed within a suitable rigid cup 42 having an axially extending post 43 which projects into a necked or restricted portion of the outer housing section 27. Post 43 is slotted and provided with a pin 44 or similar means for pivotally engaging a looped end of an axially extending tension spring 45 whose outer end is looped in pivotal engagement with a similar pin 46 rigid on axial post 47.

Post 47 is mounted for axial rotation in a suitable socket 48 formed in a cup 49 sealed with one end of a bellows 51 so that spring 45 is effectively universally and swivelly connected to flexible metal-walled bellows 51. A suitable gas tight cap 52 seals socket 48 from the interior of bellows 51 which is located within an enlarged end chamber 50 in housing section 27.

The outer end of bellows 51 is sealed with a suitable cup 53 from which extends an axial threaded post 54, preferably integral therewith, having a slot 55 across its outer end. The outer surface of cup 53 is preferably formed with a circumferential ring of serrations 56 which are adapted to receive a detent 57 formed integral with the free end of a flat spring 58 secured to the inner side of housing end wall 59.

Bellows 51 is preferably of the same size as bellows 37 and has the same effective external area exposed to atmospheric pressure. The substance under pressure within bellows 51 may be air, nitrogen or any suitable and preferably inert gas, which is preferably under atmospheric pressure.

It is possible even to use a vacuum within bellows 51 provided a suitable compression spring is employed within the bellows or other steps are taken to adjust the combination for the resultant unbalance set up between the pressure inside and outside of the bellows.

While pressure responsive elements such as bellows have been shown by way of example, it is to be understood that other forms of pressure responsive devices may be used such as sealed diaphragms, chambers, pistons and cylinders, or the like.

Wall 59 is supported on housing section 27 by means of an inwardly projecting threaded boss 58a which fits within the internally threaded outer portion of section 27. Post 54 extends in threaded engagement through a suitable axial aperture in wall 59 so that slot 55 is accessible to receive a screw driver or similar tool for adjustment purposes exteriorly of wall 59. A suitable cap 61 is secured in threaded engagement upon the outer side of wall 59 and extends over the end of post 54. Cap 61 is preferably locked or sealed in a suitable manner to prevent unauthorized access to post 54.

Housing section 27 is formed at its inner end with a recess 62 and an upstanding web formation 63. A lever 64, journaled upon web 63 by a pivot 65, is connected by a suitable lost motion pin and slot connection 66, 67 to post 43 at its upper end and extends downwardly through recess 62 (Figure 5) to abut against the end of a valve mechanism plunger stem 68 slidably supported in a wall of housing section 26. The leverage of lever 64 is preferably approximately 3 or 3½ to 1.

Stem 68 is formed at its outer end with an enlarged head 68a upon which a flat-headed disk 69, preferably of fiber or like material, is secured by a screw 71 or other suitable fastening means.

As illustrated in Figures 1 and 5, an idling fuel supply passage 72, formed in the wall of conduit 21, leads to an enlarged chamber 73 open externally of the conduit wall. Chamber 73 is aligned with aperture 33 and is internally threaded to receive a threaded hollow plug 74 having an enlarged bell-mouthed head 75 in line with and adapted to engage fiber disk 69. A suitable coil spring 76 is seated within the shouldered bore 77 of plug 74 and abuts against the head of screw 71 which is preferably flat and coplanar with the surface of disk 69.

When plug 74 is screwed tightly into chamber 73 its inner enlarged head abuts against an annular seating washer 78. Plug 74 is provided with a neck portion 74a defining an annular passage 79 with the walls of chamber 73 and having a plurality of radial passages 81 connecting passage 79 with the internal bore through plug 74.

A fuel passage 82 leads from a suitable nozzle 83 which supplies a fuel mixture from the carburetor for idling purposes, and an unobstructed fuel mixture path is provided from nozzle 83 to passage 72 by means of passages 82, 79, 81 and the bore of plug 74.

A passage 84 leads from the atmosphere or a source of substantially atmospheric pressure to chamber 73 adjacent the bell-mouth 75 for a purpose to be later described. Passage 84 preferably leads from a point in the carburetor conduit downstream of the conventional air filter so that the air entering through passage 84 is clean and free from dirt and foreign matter. The threaded engagement between plug 74 and the walls of

chamber 13 provides a substantially gas tight connection so that no gasoline fumes or liquid can escape to the outer portion of chamber 13 and no air can leak into the idling fuel mixture at this point to disturb the existing ratio of gasoline and air which has been determined by adjustment of the carburetor.

Idling passage 72 is provided with an idling jet 83 (Figure 1A) leading to the interior of conduit 21 which is preferably arcuate in form as illustrated and formed by providing a round opening in the conduit wall and fitting therein a plug 86 whose periphery is cut away to provide the arcuate shaped jet 83 which is located adjacent the downstream edge of the valve 23 when the latter is in idling position. The flow of fuel from the idling jet is thus metered in a known manner by the position of the throttle valve.

At the other side of the carburetor conduit, the wall is formed with an orifice 87 which is connected by a suitable conduit 88 to the interior of recess 29. Orifice 87 is located adjacent the edge of throttle 23 when the latter is in closed or idling position and is therefore at a point where the throttle valve edge has considerable vertical displacement with reference to the conduit wall for a predetermined angle of oscillation thereby contributing to the sensitivity and efficiency of operation of the unit.

As shown in Figure 1, orifice 87 is subjected to the full downstream vacuum when the valve 23 is in idling or closed position but when the valve is only slightly cracked open the effect of the downstream vacuum is considerably reduced. The action of the valve in controlling the operation of the "Degasser" and the added sensitivity provided by modifying the valve edge to a thin section as at 24 are fully discussed in the aforementioned patent. In this manner an unobstructed passage leads from orifice 87 to the interior of bellows 37 by means of conduit 89, recess 29, passage 31 and aperture 41 and control of the pressure transmitted along this passage is effected by the edge of throttle valve 23.

The control unit is preferably attached to the carburetor assembly as a unit by means of bolts 89 which pass through housing sections 25, 26 and 27 and are threaded in suitable bores in the wall of conduit 21. A suitable gasket 91 between housing section 25 and the outer interfitting surface of the conduit wall provides a gas tight seal when the bolts 89 are drawn tight.

Operation

In operation, with the engine running and the throttle valve 23 in idling or closed position as illustrated in Figure 1, the interior of bellows 37 is subjected to the vacuum existing in the intake manifold through orifice 87, conduit 88, recess 29, boss 28, passages 31 and 32, and aperture 41.

With the interior of bellows 37 subjected to vacuum, the external atmospheric pressure tends to collapse this bellows to the left as viewed in Figure 1. This action is resisted by the resistance of the bellows itself and mainly by the pull of spring 45. Referring to Figure 1, it will be seen that the tension of spring 45 may be regulated to vary its effect on the bellows 37 by moving pin 46 axially of the unit.

This displacement of pin 46 is effected by removing cover 61, inserting a screw driver or suitable tool in slot 55 and thereby rotating axially the whole bellows assembly at 51. The swivel connection between post 47 and bellows 75

51 prevents the spring from being wound or unwound during the above described adjustment. The adjustment is maintained against accidental displacement by the cooperation of detent 57 and serrations 66, and is maintained against unauthorized adjustment by sealing cap 61 in any suitable manner.

At the factory, this adjustment is preferably made to balance spring 45 against the vacuum within bellows 37 in such a manner that post 43 does not move to the left during normal idling vacuum in the intake manifold. Under these conditions, lever 64 is maintained stationary by the pull of spring 45, with its lower end just abutting against stem 68 with sufficient force to urge disc 69 into tight sealing engagement with bell-mouth 75. In this position, spring 76 is compressed within bore 71 and abuts against the head of screw 71.

Under normal idling conditions, there is no interruption to the flow of the fuel mixture along passages 72 and 82, there is no leakage of gasoline fumes which might cause the material of disk 69 to deteriorate, and there is no danger that any sticky powder or other substance from the fuel will leak into and clog the guide of stem 68 and thereby interfere with the operation of the unit.

Similarly, there is no air leakage past plug 74 into the fuel mixture passage and the original idling adjustment of the carburetor is not disturbed. Of especial advantage is the fact that the fiber to metal contact surface engagement at 69, 75 has not only better wearing properties than a metal to metal valve face contact, but provides a very effective gas tight seal.

When the throttle is in idling position and the engine running conditions may be such as to produce a vacuum in the intake manifold which is higher than the normal idling vacuum for which the unit has been adjusted, as where the vehicle is descending a long grade with the throttle closed, this increased vacuum is effective to cause bellows 37 to contract so that post 43 and pin 66 move to the left in Figure 1, thereby rocking lever 64 in a counterclockwise direction.

As the lower end of lever 64 moves to the right it permits spring 76 to push disk 69 away from bell-mouth 75 thereby venting the bore of plug 74 to atmospheric pressure and overcoming instantly the suction of the intake manifold which has been drawing fuel up through passages 72 and 82. The idling fuel mixture supply is thereby cut off as effectively as if a positive valve had been shut off in the idling passage, and no fuel is conveyed to the engine during these conditions of operation whereby gassing conditions are eliminated.

The above arrangement is especially advantageous because the valve opening action at bell-mouth 75 is positively carried out by spring 76 which is of sufficient strength to overcome the inertia of stem 68.

Under substantially constant atmospheric conditions spring 45 may just as well be anchored rigidly at its right end. However, as above pointed out, atmospheric pressure variations due to changes in altitude and even changing weather conditions, seriously affect operation of the unit by varying the differential between the suction inside bellows 37 and the pressure of the atmosphere. The purpose of anchoring spring 45 to the deformable pressure responsive bellows 51 is to compensate for these pressure changes

and insure uniform operation of the "Degasser" unit during all conditions of operation and atmospheric pressure.

Preferably bellows 51 is sealed with an internal pressure equal to that of the atmosphere at sea level and the spring 45 properly adjusted between posts 43 and 47. Since both bellows 37 and 51 are flexible they stretch somewhat under the tension of spring 45 but yet offer sufficient resistance to keep the spring from becoming relaxed.

The pressure within bellows 51 may be negative, but when such sub-atmospheric pressure is employed the difference between it and sea level atmospheric pressure should not exceed the total pull of the spring.

Suppose a vehicle having its "Degasser" unit correctly adjusted is driven from a locality of high atmospheric pressure to one of low atmospheric pressure. As the atmospheric pressure decreases, bellows 51 will expand to the left as viewed in Figure 1 thereby weakening the pull of spring 45 on bellows 37 to compensate for the reduced atmospheric pressure effective on the extended surface of bellows 37. The parts are so proportioned that the effective pull of spring 45 upon bellows 37 is always automatically maintained in the same relation with respect to the absolute value of the predetermined vacuum necessary to contract bellows 37 so that the idling fuel supply is shut off whenever the intake vacuum exceeds normal idling vacuum with the throttle closed.

Since both bellows 51 and 37 are preferably of the same effective external area as regards the atmosphere, the effect of changes in atmospheric pressure upon either is automatically balanced. Where reference is made herein to the bellows as being of the same size, it is meant that the external areas thereof, subject to atmospheric pressure, are substantially equal. It does not follow that both bellows must have the same number of convolutions or corrugations to have equal external areas exposed to atmospheric pressure because they may be of different diameters or have only one or have both ends exposed to atmospheric pressure.

Since the "Degasser" housing is secured to the engine which becomes quickly heated in operation, the question of expansion of the parts due to increased temperature raises a material problem. When the bellows are made small, as they preferably are, any expansion of the bellows due to temperature rises may be at least partially limited. Likewise an evacuated bellows would have little expansion due to temperature rises.

However in the present invention the expansion of the parts due to increasing temperature is preferably compensated in the following manner. Housing section 27 is preferably an elongated thin metal shell which, since section 25 is bolted to the engine, expands to the right in Figure 1 when heated. Bellows 51, rigid upon bossing wall 59, will expand to the left in Figure 1 when heated. In this manner, by choosing the proper proportions for bellows 51 and shell 27, the effect of temperature expansion may be further compensated since the outer end of spring 45 is effectively maintained against axial displacement.

All adjustments of the "Degasser" unit are preferably made with the engine and unit hot. Therefore when the engine is first started, and is cold especially in winter, the operation of the "Degasser" in cutting off the idle fuel supply is

not as critical as when the engine is operating at normal running temperature.

When the motor is cold, bellows 51 is contracted to a maximum and the pull of spring 45, also contracted, is increased to a point where it will resist even a high vacuum in the intake manifold.

This sluggishness of operation, or shut-off at a higher vacuum, is actually beneficial in the present invention in that it is desirable to keep a flow of fuel into the manifold at all times while the motor is cold. As the engine warms up, bellows 51 will expand and the "Degasser" will begin to cut off the idling fuel supply at progressively lower degrees of vacuum in the intake until it is operable just above normal idling vacuum when the engine has reached normal operating temperature.

An example of this beneficial operation is found when a vehicle is descending a long grade at relatively high speed. While the motor is hot the "Degasser" is operative to cut off the idling fuel supply but when the motor has cooled the "Degasser" parts contract to permit a resumption of flow of fuel in the idling passage and thereby keep the engine warm enough to operate smoothly when it reaches the bottom of the grade.

Modifications

30 The "Degasser" control unit illustrated in Figures 6-8 is similar to that of Figures 1-5 except that it is adapted to operate a needle valve of the type used in the idling passage of the "Degasser" disclosed in the above mentioned patent.

Referring to Figure 6, casing 27' is formed with a recess 92 bridged by a suitable pivot pin 93 upon which is journaled a lever 94 whose lower end abuts one end of a slidable valve operating stem 95. Lever 94 is slotted at 90 to form a lost motion connection with pin 66 on post 43, and is provided with a suitable apertured lug for receiving and anchoring the inner or left end of spring 45.

45 The other end of stem 95 abuts axially with the blunt end of a needle valve 96 whose conical face is normally maintained away from a suitable valve seat 96a within plug 74' by a coil spring 97, preferably conical in shape, which surrounds valve 96 and urges it to the right (Figure 6) to maintain a contact connection with lever 94 and insure instantaneous movement of valve 96 when the lever is moved. The right end of spring 97 abuts against a washer 97a fixed to 55 valve 96.

Belows adjustment post 54' extends a substantial distance beyond the housing wall 59' so that slot 55' is readily available for adjustment and the reception of a sealing wire.

60 The unit of Figure 6 differs in operation from that of Figure 1 in that the former provides a positive shut off action by pushing the needle valve 96 firmly into its seat when the suction within bellows 37 is sufficient to rock lever 94 in a clockwise direction. Otherwise the operation of these units is substantially the same.

65 The "Degasser" control unit illustrated in Figures 9-13 embodies a flexible diaphragm unit in place of bellows 37 of Figures 1-8 which may be used in installations where the unit is not subjected to conditions detrimental to the diaphragm.

70 The diaphragm base 98 is provided with a hollow boss 99 which fits into the carburetor wall aperture 29 in the same manner as aperture 28

in Figure 1. The flexible diaphragm element 101, which may be of rubber, Duprene or similar material is clamped and sealed circumferentially between an edge wall of base 98 and an annular ring 102 by means of a series of screws 103 which pass through an annular flange 104 on shell 27'. The effective area of element 101 exposed to external atmospheric pressure is preferably equal to the effective area of bellows 51' exposed to the same pressure.

Base 98 is formed with a guide bore 105 for receiving a slidable cylindrical cap 106 which cooperates with the threaded stem of a rigid diaphragm button 107 to secure the button in gas tight connection with element 101. A screw driver slot 108 is provided for tightening cap 106 upon button 107.

Button 107 is formed with an integral slotted post 109 having a pin 111 fitting within a slot 90 of lever 94 which is pivotally supported at 93 and connected to spring 45 in the same manner as above described in connection with Figure 6.

The other end of spring 45 is swivelly connected to bellows 51' in the same manner as in Figure 6. Shell 27' is closed by a threaded plug 112 having a threaded central aperture through which passes the threaded bellows adjustment post 113.

As illustrated in Figure 13, the bellows adjustment locking spring 58 is arcuate in shape and is secured at one end to plug 112 by suitable screws 114 or the like.

The lower end of lever 94 abuts against a stem 115 which is slidably mounted in a guide bore 115a passing through ring 102 and element 101 into a recessed portion of base 98 where it is provided with an integral upstanding lug 116 for abutting the end of needle valve 96. Lug 116 is also formed to cooperate with the recessed portion of base 98 to prevent rotation of stem 115 about its axis.

A pair of elongated bolts 117 pass through flange 104, ring 102 and base 98 to secure the "Degasser" unit to the carburetor wall as above described.

The operation of the unit of Figure 9 is substantially the same as the bellows type above described. A passage 118 leads from boss 99 to subject the left side of the diaphragm (Figure 9) to different pressures dependent upon the operation of the engine. Straight line movement of the diaphragm button or lever 94 is insured by the sliding fit of cap 106 within bore 105.

The embodiment of the invention illustrated in Figures 14-17 is a springless unit wherein a housing 119 is provided with a hollow boss 121 adapted to fit within recess 29 in the conduit wall of the carburetor so as to be in communication with the intake manifold. Bolts or screws 120 secure housing 119 rigidly to the conduit wall.

The open end of a flexible metal-walled bellows 122 is secured, by means of screws 123 and suitable gaskets, in gas tight relation to the left wall of housing 119 and a passage 124 leads from boss 121 to the interior of bellows 122.

Housing 119 has secured thereto an aligned shell 125 by means of screws 126 passing through mated flanges of the housing and shell. The outer end of shell 125 is closed by a threaded cap 127 provided with a central boss 128 which is threaded to receive an adjustment screw 129 whose inner end is threadedly engaged with a suitable block 131 rigid with one end of a flexible sealed bellows 132.

Screw 129 and boss 128 are provided with co-

operating serrated locking surfaces at 133 and boss 128 is apertured to permit insertion of a sealing wire 134 to prevent unauthorized tampering with the adjustment of screw 129.

5 Bellows 122 and 132 are preferably of substantially the same size and characteristics, having equal external effective areas exposed to atmospheric pressure and are interconnected by a rigid post 135 which is preferably integral with their 10 adjacent end caps 122' and 132'.

Opposite side walls of shell 125 are shouldered at 136 and provided with aligned pivot pins 137 for receiving a pair of opposed arms 138, which are bent downwardly and inwardly and are each 15 slotted at 141 to fit over oppositely projecting end portions of a pin 142 rigid with post 135.

Below post 135, arms 138 are bent together and riveted or otherwise integrally secured at 139 to provide a suitable lever extension 140 for abutting the end of a stem 150 slidable within a suitable longitudinal bore 150a in housing 119. The outer end of the stem 150 is adapted to engage the valve stem 96 of Figure 6, or may engage the plunger stem 68 of Figure 1 as desired, it being understood that lever 140 in the latter case is pivoted to rotate as lever 64 of Figure 1.

Shell 125 is provided with a recessed integral extension 143 for accommodating the lower end of lever 140 and this extension is provided with a threaded wall plug 144 aligned with stem 150. Should the valve seating faces of plug 144 which cooperate with needle valve 96 become worn or encrusted with dirt or other foreign matter, the valve can be quickly reseated by taking out plug 144 and tapping the end of stem 150 with a suitable tool to thereby forcibly thrust the conical end of needle valve 96 into seat 96a and thereby effectively reform the valve seat. If stem 150 should become frozen or sticky in operation, plug 144 can be removed and any suitable tool inserted to force the stem axially along its guide until it is loose. It is to be understood that a plug as shown at 144 may be used with any of the modifications herein shown.

45 In operation, the flexible walls of the bellows 132 act as resilient means for urging lever 140 in a counterclockwise direction and screw 129 is adjusted until lever 140 is just in engagement with the inner end of stem 150 at the normal 50 idling vacuum. By reason of bellows 122 and 132 having substantially equal external effective areas, they are both affected the same by changes in atmospheric pressure and correct operation of the device is insured under different atmospheric pressures.

Automatic temperature compensation

The device illustrated in Figures 18 and 19 is 60 preferably designed to be used with a pressure compensating control of the type illustrated in Figure 14 but it will be understood that it may readily be applied to any of the other embodiments of the invention.

A pair of mated housing and shell members 65 119' and 125', respectively, are secured rigidly together, as by spaced bolts 126'. A bellows 122' having walls of thin flexible metal is secured in fluid tight relation upon an end wall of housing 119'. A passage 124' leads from hollow boss 121' 70 to the interior of bellows 122', and boss 121' is designed to fit within recess 29 as above described.

A second bellows 132' having walls of thin flexible metal and being of substantially the same shape and size as bellows 122' is adjustably supported upon a removable end plug 127' of shell 125'

by means of a suitable adjustable support 129' which is preferably the same as screw 129 described above in connection with Figure 14.

Bellows 122' and 132' are somewhat shorter than bellows 122 and 132 of Figure 14, but are similarly interconnected by a rigid axial post 151. A diametral pin 152 extends through post 151 with its opposite ends projecting a substantial distance beyond post 151.

An elongated pin 153 extends across the upper part of shell 125' generally parallel to pin 151 and preferably in vertical alignment therewith. The opposite ends of pin 153 project outside the shell and are preferably burried to prevent accidental displacement of the pin.

A temperature responsive lever 154, which is preferably a generally Y-shaped bimetallic strip (Figure 19) has the end portions of the arms of the Y curled about the opposite ends of post 152 at 155 so that lever 154 is rotatably connected at one end to post 151.

From pin 152 the arms of the Y extend upwardly past one side of pin 153 and then curve around and downwardly past the other side of pin 153. Below post 151, the arms of the Y are brought together to form a single leg 156 which is inclined outwardly and downwardly to contact the inner end of valve stem 150 as illustrated in Figure 18. Pin 153 thereby serves as a fulcrum for lever 154 and the spacing of pins 152 and 153 as well as the length of lever 154 can be selected to give any desired mechanical advantage. Lever 154 is Y-shaped to clear post 151 as the former rocks about its fulcrum and the above described structure provides substantially a lost motion connection between lever 154 and fulcrum pin 153.

If no temperature compensating means is employed, expansion of bellows 132' due to heat from the engine will shift post 151 an appreciable amount to the left since bellows 132' expands faster and more in response to temperature rises than shell 125'. This would cause premature cut-off of the idling fuel supply during operation of the engine.

In the above described embodiment, because of the fact that the whole of lever 154 or the lower part comprising arm 156 is made up as a bimetallic thermostatic element of any well known form with the strip having least expansion due to heat located on the right side of arm 156 or the inside of the loop formed by lever 154 in Figure 18, when heated, lever 154 bends in such a manner as to displace arm 156 to the right in Figure 18. The parts are so proportioned in length, shape and position that this displacement of arm 156 to the right in Figure 18 compensates for any movement of post 151 to the left due to expansion of bellows 132' and there is no relative movement between arm 156 and stem 150 due to temperature changes. In a correct design, one movement offsets the other.

A device of this kind has been operated in an advantageous manner under conditions involving a change in altitude of approximately 7000 feet and a difference in engine temperatures of approximately 150°. During these tests, the operation of the "Degasser" took place within a vehicle speed range of 2 1/2 miles per hour.

However, since the "Degasser" operated on a cold engine at vehicle speeds which were 2 1/2 miles per hour higher than those at which it operated on a thoroughly warm engine, this slight change of operation at low temperatures is quite advantageous in that it assists speedy warming up of the engine and prevents the motor from

becoming too cold while the vehicle is traveling down long grades as to interfere with operation of the motor when the bottom of the grade is reached.

5 The above described "Degasser" units are especially adapted for use with throttle controlled "Degasser" systems as above pointed out and are operable upon any desired type of valve mechanism in the idling fuel supply passages.

10 In each unit, the effect of varying atmospheric pressure due to any cause is automatically compensated so that uniform operation of the "Degasser" is insured.

15 It is now common practice to install "Degassers" on trucks and buses which make long hauls because of the tremendous savings in gasoline and the advantageous operating conditions, and the present invention insures that these vehicles will operate just as efficiently in mountainous and desert regions as on the more level and more temperate routes.

20 It is to be understood that the various bellows control units are not limited to use in the "Degasser" control field but may be used for controlling any valve whose operation is affected by variations in atmospheric pressure or temperature. The invention is especially adapted for use in controlling the fuel supply to airplane engines where abrupt changes in altitude constantly take place and where it is absolutely necessary that the fuel supply control be accurate, dependable and efficient in operation.

25 The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

30 What is claimed and desired to be secured by United States Letters Patent is:

35 45 1. In a compensating device for controlling the operation of a fuel supply restricting means in a carburetor or the like, a deformable pressure actuated element; a fuel supply valve operating lever controlled by said element; a spring connected to said element at one end for governing the action of said element; an expansible sealed bellows swivelly connected to the opposite end of said spring and means for adjusting the tension of said spring.

40 55 2. In a carburetor having a passage through which fuel is drawn by suction to an engine when the engine throttle is in idling position, a port in said passage leading to the atmosphere; a closure member for said port comprising a slideable plunger having a sealing face of fibrous or like material for cooperating with the edges of said port to form a normally fluid tight joint; resilient means normally urging said member away from said port; means for retaining said member over said port against the action of said resilient means; pressure responsive means for rendering said retaining means inoperable upon said member whereby said member is forced away from said port by said resilient means to admit atmospheric pressure to said passage and thereby

60 65 70 75 cut off the flow of fuel due to suction.

3. In combination with a carburetor having a passage adapted to be connected to the fuel intake of an internal combustion engine, a throttle in said passage; means for supplying fuel to said

engine when the throttle is in idling position comprising an idling jet positioned to discharge fuel into said passage at a point posterior of said throttle; pressure responsive means responsive to suction in said intake manifold controlling said fuel supply; and means for automatically regulating said pressure responsive means to compensate for changes in temperature and atmospheric pressure to which said pressure responsive means is exposed to insure correct operation of said pressure responsive means.

4. In a carburetor having a passage adapted to be connected to the fuel intake of an internal combustion engine, a throttle in said passage, an idling jet positioned to discharge fuel into said passage at a point posterior of said throttle, a valve for controlling fuel flow through said idling jet, a pressure responsive device for operating said valve comprising a pressure responsive element, resilient means to oppose movement of said element in a direction to close said valve, and a control lever pivotally connected to said pressure responsive element and connected to operate said valve or like means, said lever comprising a thermo-responsive element.

5. In combination with a carburetor having a passage adapted to be connected to the fuel intake of an internal combustion engine; a throttle in said passage; means for supplying fuel to said engine when said throttle is in idling position comprising an idling jet positioned to discharge fuel into said passage at a point posterior of said throttle; and pressure operated means responsive to vacuum in said intake manifold to control said idling fuel supply from a full opening to a full closure, said pressure operated means being arranged to shut off said idling fuel supply at a lower predetermined vacuum at a predetermined temperature of the ambient atmosphere corresponding to the temperature of the engine when cold than at an ambient atmospheric temperature corresponding to the normal operating temperature of said engine.

6. In combination with an engine carburetor, pressure responsive means for controlling the flow of fuel to said engine comprising an elongated thin-walled metal support rigidly secured at one end to said carburetor, an interior end wall at the free end of said support and a sealed bellows rigidly secured at one end to said interior end wall so that expansion of said support and said bellows due to heat from the ambient atmosphere will take place in opposite directions and in such amount as to automatically compensate for the effect of changes in the temperature of the ambient atmosphere upon said pressure operated means, said lever comprising a thermostatic strip to compensate for the temperature changes.

7. In combination with a carburetor having a passage, a throttle in said passage, an idling jet in said passage posterior of said throttle for supplying fuel to said engine during idling conditions, means for valving the flow of fuel through said idling jet from a complete shut-off to a complete opening, a pressure responsive element operatively connected to the intake manifold of said engine and means including a lever interconnecting said valving means and said element, said lever comprising a thermostat strip deformable in response to temperature changes to vary the effect of said element on said valving means at different temperatures.

8. A valve control device comprising a housing having opposed walls, a deformable bellows secured on one wall and provided with a conduit connecting it to a source of fluid pressure, a second deformable bellows adjustably mounted on the opposite wall, a rigid member interconnecting adjacent ends of said bellows, a pivoted lever within the housing operatively connected to said rigid member and a slidably valve control rod adapted to be actuated by said lever.

WILLIAM E. LEIBING.
